LINKING MACHINE FOR KNITTED GOODS

Achille Peloggio, Brignano d'Adda, Italy
(% Modiana, Via Meravigli 16, Milan, Italy)

Filed Oct. 15, 1962, Ser. No. 72,110

Term of patent 7 years

(Cl. D47—5)

FIG. 1 is a front perspective view of a linking machine for knitted goods, showing my new design;

FIG. 2 is a side elevational view;

FIG. 3 is a bottom plan view of the base portion only;

FIG. 4 is a top plan view; and

FIG. 5 is a rear elevational view thereof.

The dominant features of my design reside in the portions shown in full lines and more specifically in the configuration of the support frame.

I claim:

The ornamental design for a linking machine for knitted goods, as shown and described.
